UNITED STATES PATENT OFFICE.

PHILLIP HIEN, OF CHICAGO, ILLINOIS.

AUTOMATIC TRAIN-PIPE COUPLING.

No. 872,514.

Specification of Letters Patent.

Patented Dec. 3, 1907.

Application filed February 26, 1906. Serial No. 302,908.

To all whom it may concern:

Be it known that I, PHILLIP HIEN, a citizen of the United States, residing at Chicago, county of Cook, State of Illinois, have invented a certain new and useful Improvement in Automatic Train-Pipe Couplings, and declare the following to be a full, clear, and exact description of the same, such as will enable others skilled in the art to which it pertains to make and use the same, reference being had to the accompanying drawings, which form a part of this specification.

My invention relates in general to train pipe couplings, and more particularly to couplings for automatically uniting the corresponding train pipes on adjoining cars when the draw bars of the cars are coupled, and automatically disconnecting the train pipes on the respective cars when the uncoupling of the draw bars permits the cars to separate.

In automatic train pipe couplings the gaskets in which the pipes terminate should only be brought into engagement when in alignment, and should be kept out of contact with each other during their relative movement into and out of engagement so as to protect them from being torn out of the coupling heads and to prevent their being so worn by usage as to permit leakage. The coupling heads should also be so tightly held in engagement that the relative movement between the adjacent ends of the coupled cars will produce no movement between the registering gaskets.

The primary object of my invention is to provide an automatic train pipe coupling which will protect from injury the terminal gaskets of the pipes in coupling and uncoupling, which will move the gaskets directly towards and away from each other as they couple and uncouple, and which will retain the aligned gaskets in close contact free from any relative movement.

A further object of my invention is to provide an improved automatic train pipe coupling which will be comparatively simple in construction, inexpensive in manufacture and efficient in operation.

The embodiment of my invention herein disclosed may be generally described as comprising a supporting bracket depending from and rigidly connected to the draw bar of a car, a drum extending through and longitudinally movable but non-rotative with re-

spect to said bracket, a coupling head rigidly supported at the outer end of said drum and having an inclined surface in which the train pipes terminate, a flaring guide surface on said coupling head, a spring interposed between said bracket and the coupling head, a projection on the coupling surface adapted to be engaged by the coupling surface on the co-operating coupler for retaining the gaskets out of contact when coupling and uncoupling, the coupling surface having ribs and corresponding grooves for interlocking with similar ribs and grooves in another coupler, and a spring adapted to be engaged by a lug on the end of the coupling surface of a co-operating coupler to retain the coupling surfaces on the engaged couplers in close contact.

My invention will be more fully described hereinafter with reference to the accompanying drawings in which the same is illustrated as embodied in a convenient and practical form, and in which,

Figure 1 is a side elevational view showing so much of the draw bars and car frames as is necessary to illustrate the connection of my invention therewith; Fig. 2 a horizontal sectional view showing the pipe couplings on adjoining cars interlocked; Fig. 3 a front elevational view of one of the couplings; Fig. 4 a sectional view on line 4—4 Fig. 3; and Fig. 5 a cross sectional view on line 5—5 Fig. 2.

The same reference characters are used to designate the same parts in the several figures of the drawings.

Reference characters A' A' designate the longitudinal center sills of two cars united by means of the draw bar couplers CC.

c, c designate mechanism for lifting the locking pins of the draw bar couplers.

c' c' designate the yokes or straps which are rigidly connected to the inner ends C' C' of the draw bars, and surround the draft gear and buffing apparatus.

The foregoing constructions are well known in the art and need not be further described in detail.

The train pipe coupling mechanism is the same on each car and hence it will only be necessary to describe in detail the mechanism applied to one car.

D indicates a bracket for supporting the train pipe coupling and comprises an arm D' extending upwardly to the under surface

of the draw bar coupler C to which it is secured in any suitable manner by means of screws d' .

5 D^2 indicates an arm extending rearwardly from the bracket D which engages at its inner end the lower end of the yoke c' .

D^3 indicates a collar formed in two parts secured around the draw bar adjacent the ends of the yoke c' .

10 d^3 indicates a bolt for securing the two parts of the collar together above the draw bar while d^2 indicates a bolt securing the two parts of the collar together below the draw bar and for also supporting the inner end of 15 the arm D^2 . The bracket D is consequently securely attached to the draw bar so as to move therewith relatively to the car frame. By providing the arms D^2 the bracket may be secured to the draw bar of any standard 20 car without requiring any change in the present construction thereof.

F indicates a drum extending through a single opening in the bracket D. The drum F is provided with longitudinal grooves 25 f therein into which extend projections d on the bracket D, as clearly shown in Fig. 5. The drum is consequently permitted to move longitudinally relatively to the bracket and to swing laterally with respect thereto owing 30 to the cross section of the drum being slightly less than the opening through which it extends in the bracket. The coöperating projections d and grooves f prevent the drum from rotating within the bracket, but permit 35 a slight oscillatory movement.

At the outer end of the drum F is a coupling head E between which and the bracket D is interposed a spring G. In order that the tension of the spring may not disengage 40 the drum from the bracket a suitable stop, such for instance as a pin g extends through the drum on the opposite side of the bracket from the spring. The coupling head is provided with an inclined coupling surface E' 45 through which ports extend forming terminals of the train pipes. Short sections of pipe L are secured in the ports in the coupling surface E and surrounding the ports are gaskets l located in seats in the coupling surface. Short sections of hose are secured 50 around the pipe sections L in any suitable manner, as for instance by clamping rings n . The free ends of the hose sections N are provided with the usual forms of metallic hand 55 couplings o which are adapted to interlock with similar couplings on the ends of the usual sections of hose O which depend from the ends of the metallic pipes P. The pipes P are usually three in number, one for actuating the brakes, another for operating the signal, and the third for steam. Such pipes are usually provided with angle cocks p at the ends thereof.

The coupling surface E' is provided with a 60 lug e' and a corresponding slot e^2 . The end

of the coupling surface is provided with ribs e^5 , e^6 while the portion thereof above and below the lug e' is provided with corresponding grooves e^4 , e^4 . The forward end e of the coupling surface is wedge-shaped conforming 70 to a wedge-shaped pocket e^3 formed in the coupling head at the rear of the grooves e^4 .

K indicates a leaf spring one end of which is rigidly secured to a block H carried at the rear end of the drum F. A bolt h extends 75 through the spring K, the block H, and rear end f^2 of the drum. Pins h' are preferably provided on the block H which enter recesses in the supporting portion of the drum. In order that the spring may be securely attached to the block a clip k is interposed between the spring and the head H' of the bolt. The spring K extends through an opening in the flaring guiding surface E^3 which projects from the coupling head E. The extreme end 80 k^2 of the spring over-laps a flange on the flaring guide E^3 .

The operation of my invention is as follows: The bracket D is secured to the draw bar by inserting the screws d' through the arm D^2 into engagement with the coupler head and by securing the collar D^3 around the shank of the draw bar with the end of the arm D^2 against the end of the yoke thereby transferring the strain imposed upon the 90 bracket D to the end of the yoke. The drum F is inserted through the opening in the bracket and the pin g secured in position to prevent the withdrawal of the drum from the bracket. The spring K together with 100 the block H is then secured to the extension on the rear of the drum by means of the bolt h . The tension of the spring G projects the pipe coupling slightly beyond the draw bar coupler so that when the cars are forced together and the draw bars thereof automatically coupled, the coupling surfaces of the pipe couplings will engage and place the springs G around the respective drums under 105 tension. This tension of the springs G 110 serves to at all times retain the pipe couplings in close contact. In order that the pipe couplings may interlock, each is provided with the laterally upwardly and downwardly flaring guide E^3 which receives 115 the point e of the coöperating coupling, consequently even though the pipe couplings on the adjoining cars are not in horizontal or vertical alinement, the flaring guides will insure the coupling surfaces being brought into 120 exact registry. The wedge-shaped end e on each coupler is forced into the wedge-shaped pocket e^3 on the coöperating coupling, thereby retaining the coupling surfaces in tight engagement. The engagement between the lug e^6 on each coupler with the 125 spring K on the coöperating coupler also serves to retain the coupling surfaces in contact.

In order that the coupling surfaces will be 130

held apart during their relative movement in coupling or uncoupling thereby preventing wear upon the gaskets, each coupling surface is provided with ribs e^5 around the outer end 5 thereof and with a lug e' which, when the gaskets are in alinement, are received within the grooves e^4 and recesses e^2 respectively on the coöperating coupling surface thereby permitting the gaskets to be brought into 10 close contact. It will be observed that first the ribs e^5 and subsequently the lugs e' retain the surfaces apart until the gaskets are in registry when they are permitted to come into contact by reason of the ribs being received in the grooves and the lugs in the recesses. The engagement between the ribs e^5 and grooves e^4 prevents the coupled surfaces moving relatively while coupled. The movement of the ends of the coupled cars 20 with respect to each other produces no movement between the coupled surfaces, but is compensated for by the play between the drums and supporting brackets.

When the cars are uncoupled and are 25 moved apart, the pipe couplings are disconnected by reason of the pins g engaging the adjacent brackets which results in the drums moving with the respective cars and consequently away from each other.

30 When only one of the two coupled cars is provided with an automatic pipe coupling the usual sections of hose O on the car provided with the automatic pipe coupling, are detached from the sections of hose N of the 35 automatic coupling and are connected in the usual manner with the sections of hose O on the adjoining car. It is therefore evident that the train pipes on a car provided with my automatic coupling may be readily 40 coupled in the usual manner with the train pipes on an adjoining car or may be coupled to the sections of pipe N of the automatic coupler, thereby obviating the necessity of providing a car equipped with my improvement with two sets of sections of hose, one 45 leading to the automatic coupler and the other for use when the adjoining car is not provided with my improved automatic coupler.

50 The springs G and springs K coöperate in retaining the coupling surfaces in close contact. Either of the springs alone would accomplish the result and consequently should either spring be disabled the other will retain 55 the union intact between the couplings.

From the foregoing description it will be observed that I have invented an improved automatic train pipe coupling by means of which, the train pipes on adjoining cars will 60 be automatically united coincidently with the coupling of the draw-bars, in which the gaskets in which the train pipes terminate will be prevented from injury during the coupling and uncoupling operations, and in 65 which the movement between the coupled

cars will produce no movement between the coupled surfaces in which the train pipes terminate.

Having now fully described my invention, what I claim as new and desire to secure by Letters Patent is:

1. The combination with a railroad car, of a train pipe coupling head supported beneath said car, a coupling surface on said head in which the train pipes terminate, means for holding said coupling surface out of contact with a coöperating coupling surface during the relative movement of the surfaces in coupling and uncoupling, and means for forcing the alined terminals of the train pipes 80 into close contact, said latter means comprising a flaring guide having a resilient wall.

2. The combination with a railroad car, of a train pipe coupling head supported beneath said car, a coupling surface on said head in which the train pipes terminate, ribs on said coupling surface adapted to engage a coöperating coupling surface during the movement of the surfaces into and out of engagement, said coupling surface having grooves therein 90 to receive said ribs when the train pipe terminals in the respective coupling surfaces aline, and means for retaining the coupling surfaces in contact.

3. The combination with a railroad car, of a train pipe coupling head supported beneath said car, a coupling surface on said head in which the train pipes terminate, ribs on said coupling surface, a lug on said coupling surface at the rear of said ribs, said coupling surface having grooves corresponding to said ribs and a recess corresponding to said lug whereby when coöperating coupling surfaces are moved relatively in coupling and uncoupling the terminals of the train pipes will be 105 held apart, and means for forcing said coupling surfaces into contact with a coöperating coupling surface when said ribs and lug register with said grooves and recesses.

4. The combination with a railroad car, of a draw bar operatively connected thereto, of a bracket depending from and secured to said draw bar, a train pipe coupling head supported by said bracket so as to move longitudinally with respect thereto, a coupling surface 115 on said coupling head in which the train pipes terminate, and a spring interposed between said coupling head and said bracket for retaining said coupling surface in contact with a coöperating coupling surface on an 120 adjoining car.

5. The combination with a railroad car, of a draw bar operatively connected thereto, of a bracket depending from and secured to said draw bar, a train pipe coupling head supported by said bracket so as to move longitudinally with respect thereto, a coupling surface 125 on said coupling head in which the train pipes terminate, means on said coupling surface for retaining the train pipe terminals 130

thereon out of contact with the terminals on the coöperating coupling surface during the relative movement of such surfaces into and out of engagement, a flaring guide projecting from said coupling head adapted to receive the end of a coöperating coupling surface, and a spring interposed between said bracket and coupling head for retaining the coupling surface thereon in contact with a coöperating coupling surface.

6. The combination with a railroad car, of a train pipe coupling head supported thereon, a coupling surface on said head in which the train pipes terminate, a lug at the end of said coupling surface, a flaring guide carried by said coupling head having a resilient wall in position to be engaged by the lug on the end of the coöperating coupling surface, and thereby retain said surfaces in close contact.

7. The combination with the draw bar of a railroad car, of a bracket secured to said draw bar, a drum extending through an opening in said bracket, ribs on said bracket projecting into longitudinal grooves in said drum, a coupling head supported at the outer end of said drum, a coupling surface on said head in which the train pipes terminate, a flaring guide secured to said coupling head, and a spring interposed between said bracket and said coupling head for retaining the coupling surface in contact with a coöperating coupling surface.

In testimony whereof, I sign this specification in the presence of two witnesses.

PHILLIP HIEN.
